WATER-TUBE BOILER.

No. 866,034.

Specification of Letters Patent.

Patented Sept. 17, 1907.

Application filed September 27, 1906. Serial No. 336,397.

To all whom it may concern:

Be it known that WILLIAM SELLERS, deceased, late a citizen of the United States of America, residing in the city and county of Philadelphia, in the State of Pennsylvania, and I, BENJAMIN D. COPPAGE, a citizen of the United States of America, residing in Wilmington, in the county of Newcastle and State of Delaware, have invented a certain new and useful Improvement 5 in Water-Tube Boilers, of which the following is a true 10 and exact description, reference being had to the accompanying drawings, which form a part thereof.

Our present invention relates to boilers of the so-called water-tube type and has for its object the production of a boiler which is a highly efficient steam 15 generator and at the same time is simple and durable in construction and may be made and installed at a low cost.

In carrying out our invention we provide one or more sets of tubes or pipes. The ends of each tube are at 20 different levels and the lower ends of the tubes in each set are connected at different levels into a chamber or header, which we may therefore call the lower header, and their higher ends are connected at different levels into a second chamber or header which we may for this 25 reason call the upper header. Means are provided for feeding water into the boiler, so that the water level in the lower header is maintained above the lower ends of some of the tubes and below the lower ends of others. The steam generated by the boiler is withdrawn as required 30 by the conditions of service from the upper end of the lower header. Suitable means are provided for heating all of said tubes.

In operation, circulation is set up through the lower tubes from the lower header to the upper header and in 35 a reverse direction through the upper tubes. The steam generated in the tubes through which the water flows into the upper header causes the latter to be filled with a mixture of water and steam of a specific gravity considerably less than that of the water in the first 40 header. This mixture of steam and water flows into the upper ends of some of the upper tubes and back toward the lower header. The water thus entering the upper ends of some of the upper tubes is either converted into steam therein or carried back by gravity 45 into the lower header. Steam collecting in the upper end of the upper header passes back into the lower header through such pipes as have both their ends submerged. This steam, while passing back to the lower header is dried and more or less super-heated by 50 such passage, at the same time it serves to prevent the tubes through which it passes from being burned out by the heat of the furnace.

In a boiler constructed as above described it will be observed that all of the tubes throughout their length

are heating units effectively arranged in conjunction 55 with the headers for the production of dry steam. In a boiler of this character, the large separating steam and water reservoir heretofore employed in water-tube boilers and connections to the same are dispensed with. This results in a marked economy of material and hence 60 a decrease in the cost of the boiler, and furthermore by doing away with the large reservoir filled with water and steam, loss of heat by radiation is decreased and consequently the efficiency of the boiler is increased.

The various features of novelty which characterize 65 our invention are pointed out with particularity in the claims annexed to and forming a part of this specification. For a better understanding of our invention, however, and the advantages possessed by it, reference may be had to the accompanying drawings and de- 70 scriptive matter in which we have illustrated and described forms in which our invention may be embodied.

In the drawings Figure 1 is a sectional elevation of one form of boiler embodying our invention. Fig. 2 is a side elevation and Fig. 3 an end elevation of another 75 form of boiler embodying our invention and Fig. 4 is an elevation of the boiler shown in Fig. 1 illustrating somewhat diagrammatically the means which may be employed for maintaining the desired water level in the boiler.

Referring first to the construction shown in Fig. 1, A represents the upper header and B represents the lower header. The tubes C connecting the headers are in the form shown all inclined to the horizontal floor D and parallel to each other. It will be understood that back 85 of each of the tubes C, shown, may be a row of similar tubes connected into the headers A and B at the same levels. The boiler structure proper is supported on suitable foundations E, and diaphragms or partitions F are provided for causing the heated gases from the fire 90 on the grate D to pass among the tubes in the direction indicated by the arrows, escaping through the covering H of the boiler housing through the chimney passage I. The steam generated in the boiler is withdrawn through the service connection indicated at J. K and K' are removable parts of the boiler housing. The proper apparent water level, that is, the water level which would be shown by a water glass, is indicated by the line L, L. As a matter of fact, in the upper header A, a bubbling mixture of water and steam extends above the line L, L 100 to about the line M.

In the construction shown in Figs. 2 and 3 the lower header is divided into four sections A¹ each of which is connected to the appropriate one of a corresponding group of upper header sections B¹ by a set of tubes C, one tube C being in line with each hand hole cover C¹ shown in Fig. 3. The upper ends of the sections A¹ are connected to a steam reservoir N by pipes A². The

steam service connection J¹ leads from the reservoir N. The lower ends of the sections are connected to a water reservoir O by pipes A³.

Any suitable means, either manually controlled or 5 automatic may be employed for maintaining the water level in either of the forms of the boiler described, at the desired level.

In Fig. 4 we have shown somewhat diagrammatically, 10 automatic means for feeding water into a boiler to maintain the water level therein constant, substantially as disclosed in a patent to Squire, 647,683, granted April 17, 1900.

This apparatus may be briefly described as follows: 15 Q represents a pipe for conveying water from a suitable source of water under pressure to the boiler.

Q¹ is a valve controlling the flow of water through the pipe Q. Steam admitted to a chamber in the valve Q¹ through a pipe Q² tends to close it against the action of the water pressure in the pipe Q which tends to hold the 20 valve open.

Q³ represents piping etc. connected at its upper end to the boiler above the maximum water level and at its lower end to the boiler below the minimum water level.

Q⁴ represents piping connected to Q³ above the water 25 level at Q⁵ and below the water level at Q⁶, which, by its changes in length due to the varying proportions of steam and water in it as the water level in the boiler changes serves to move a valve Q⁷ to supply steam from the pipe Q⁸ to the pipe Q² when the water level in the 30 boiler is high and to connect Q² to the exhaust pipe Q⁹ when the water level is low.

It will of course be understood that any other suitable means may be employed for automatically, or otherwise, maintaining the water in the boiler at the desired 35 level.

Having now described our invention, what we claim as new and desire to secure by Letters Patent is,

1. In a water tube boiler, a set of inclined tubes arranged one above the other, a header connecting the upper 40 ends of said tubes, a second header connecting the lower ends of said tubes, and means for supplying heat to all of said tubes, said boiler being organized for operation with the water level in said second header below the corresponding ends of some of said tubes.

45 2. In a water tube boiler, a set of inclined tubes arranged one above the other, a header connecting the upper end of said tubes, a second header connecting the lower end of said tubes, means for supplying heat to all said tubes and means for maintaining the water level in said 50 second header below the corresponding ends of some of said tubes, and a steam device connection leading from the upper end of said second header.

3. In a water tube boiler, a chamber or header, a second chamber or header, a set of tubes extending between said headers, said tubes being connected into each header at different levels, and each tube being connected into said second header at a level below that at which it is connected to the first header, means for feeding water to the boiler to maintain the water level in the second header above the corresponding ends of some of said tubes, means for heating all of said tubes, and means for withdrawing the steam generated in said boiler from the upper end of said second header. 55

4. A water tube boiler consisting of a pair of headers, 60 a set or sets of inclined connecting tubes, the tubes in each set being arranged one above the other, and means for withdrawing all the steam generated by said boiler from the header to which the lower ends of the tubes are connected. 65

5. In a boiler, a set of inclined tubes, arranged one 70 above another, a header into which the lower ends of the tubes open, a second header into which the upper ends of the tubes open, means for maintaining the water level below the lower ends of certain of said tubes, and means for withdrawing the steam generated by the boiler from the header connected to the lower ends of the tubes. 75

6. In a steam boiler, a header, tubes opening into said 80 header at different levels, and a second header into which said tubes open, each tube entering said second header at a level below that at which it enters the first header, said boiler being organized for operation with the water level in said second header below the corresponding ends of some tubes and above that of others. 85

7. A water tube boiler without a steam and water reservoir, consisting of a pair of headers, a set or sets of connecting tubes extending between said headers, each tube opening into the two headers at different levels, and the different tubes of each set opening into the same header at different levels, and a main steam passage leading from the header to which the lower ends of the tubes are connected for withdrawing from the boiler all the steam generated by it. 90

8. In a steam boiler, a header, tubes opening into said header at different levels, a second header into which said tubes open, each tube entering said second header at a level below that at which it enters the first header, said boiler being organized for operation with the water level in said second header below the corresponding ends of some tubes and above that of others, and a main steam passage leading from the said second header for withdrawing from the 100 boiler all the steam generated in it. 95
